DRYING ARTIFICIAL SILK PACKAGES

Karl Moog, Obernburg-on-the-Main, Germany,
assignor to American Enka Corporation, Enka,
N. C., a corporation of Delaware

Application June 27, 1934, Serial No. 732,715
In Germany July 4, 1933

2 Claims. (Cl. 34—24)

This invention relates to a process of and an apparatus for drying artificial silk in package form, and more particularly to such process and apparatus by which unsupported packages of artificial silk are caused to be uniformly contracted during drying.

In the past, it has been the practice to subject freshly spun packages of artificial silk to washing and other similar wet treating processes while in package form. Subsequent to the wet treatment of the packages they were dried and according to the older procedures during the drying the packages were retained in the spinning pots or on bobbins, or as an alternative the packages were placed on drying supports such as the supports employed when drying skeins of artificial silk. Another of the heretofore used methods of drying the packages involved the flattening of the cakes together and the passing of these cakes onto drying frames. In all of these past modes of operation the drying progressed throughout the bodies of the packages in substantially all directions.

One decided disadvantage encountered in the former methods of drying the artificial silk packages was that the thread in the dried packages did not possess uniform dye absorptive characteristics. The reason for non-uniform dyeing of the thread in packages which were dried under conditions as above set forth is attributable to the variable contraction which occurred throughout the respective packages during such drying. When a drying agent is permitted to contact with a package of artificial silk from all directions, the outer layers of the package cannot contract to the same extent as the inner layers thereof since the outer layers cannot shrink freely due to the interior of the package being still moist and more or less rigid with the result that the filaments or thread of the outer layers meet substantial resistance from the inner layers.

This invention therefore, has as an object the provision of a method of overcoming the above stated difficulties and it contemplates the provision of an improved apparatus for conveniently carrying out the method.

A further object of the present invention is the provision of an apparatus wherein the drying medium or agent is passed through the packages from the inside to the outside only.

Other advantages and objects will be apparent from the following detailed description when considered in connection with the accompanying drawing wherein:

Fig. 1 is a perspective view of an apparatus embodied in the invention.

Fig. 2 is a cross section taken on line 2—2 of Fig. 1 illustrating the position of the spacer plates with respect to the artificial silk package 5 prior to the drying operation, and

Fig. 3 is a view similar to Fig. 2 showing the relation of the spaced plates with respect to the artificial silk packages after the drying operation has been substantially completed.

The invention may be more readily understood by referring to the drawing wherein 10 indicates a metallic container having a base 11. This base 11 contains a plurality of orifices 12 which are arranged in such a way that the artificial silk 15 packages 13 may be placed in juxtaposition thereon with their central openings 14 arranged directly above the orifices 12.

A ledge or ridge-like support 15 extends inwardly from the interior walls of the container 20 10 and the ledge may be formed integral with the container walls or it may be adjustably fastened to the walls. The ledge is arranged parallel to the base member 11 and is arranged at a distance therefrom slightly less than the height of 25 the respective artificial silk packages prior to their drying so that a spacer plate or support 16 may come to rest upon the ledge and be supported thereby after the packages on the base 30 are dried. A series of the spacer plates or supports 16 are employed when it is desired to dry a plurality of layers of artificial silk packages simultaneously by having the layers positioned one above the other.

Each of the spacer plate elements 16 are constructed with a base 17 and sides 18, and in order to successfully practice the present process the height of the sides 18 is predetermined and is slightly less than the height of the artificial silk packages prior to their being dried. The initial 40 difference in the height of the spacer plates and the height of the packages is such that the heights after the drying of the packages are substantially the same. Therefore, when these spacer plates 45 16 are first placed upon the respective layers of packages, the packages themselves will sustain the weight of the spacer plates and other packages which may be positioned thereabove.

Each of the spacer plates 16 has its base 17 50 formed with a series of orifices 19 in such a manner that when several layers of packages are positioned within the container, the axes of the packages may be axially arranged with each vertical row having their center openings communi- 55

cating through the respective orifices in the spacer plates.

It will be clear from the above that the apparatus as described is such that several advantages can be realized by drying the packages therein. When the drying medium is passed through the openings either from the top to the bottom of the container, or vice versa, the drying of each package takes place in a substantially uniform manner from the inside to the outside thereof. Due to this manner of drying, the inner layers of filaments or thread in the respective packages commence drying and therefore shrink first and as the drying proceeds to the outer part of the package the resistance from the inner part will consequently be eliminated and will therefore permit of uniform contraction throughout the body of the package.

In practicing the present method in the apparatus referred to in the drawing, it will be seen that when a drying medium such as warm air is passed through the cakes or packages, the heights of the respective cakes will gradually decrease, and the base 17, of each spacer plate will accordingly gradually sink until it is supported by the sides 18 of the spacer plate next below. By such an arrangement, the paths of the drying medium are at all times restricted to the zone within the channel formed by the thread free space within the interior of the vertical rows of packages and the openings of the spacer plates therebetween, and therefore, the drying action will at all times be substantially completely taking place from the inside to the outside of the packages.

It will of course be appreciated that the lowest spacer plate settles upon the ledges as each of the other plates settles upon the sides of the plate next below it. A cover 20 may be used upon the upper layer of packages in place of a type of spacer plate otherwise employed.

Whereas the drawing discloses the side members of each of the spacer plates as constituting the supports for the adjacent spacer plate thereabove upon the completion of the drying operation, any other suitable supporting means may be employed which will provide for the successful performance of the drying action when carried out in accordance with the present invention.

What I claim is:

1. The method of drying packages of artificial silk the respective interiors of which are in unsupported condition comprising arranging a plurality of wet interiorly unsupported packages of artificial silk in a vertical column with spacer plates therebetween, with the packages each supporting the column thereabove, passing a drying medium centrally through the column of packages while avoiding any substantial contact of the drying medium with the exterior surfaces of the packages, continuing the passing of the drying medium through the interior of the column of packages and thereby gradually effecting a progressive drying of the packages from their interiors to their respective exteriors with the resultant contraction and decrease in the height of the respective packages, and effecting the transfer of the load of the column above from the lower packages shortly prior to the period of maximum contraction of the packages.

2. The method of drying packages of artificial silk the respective interiors of which are in unsupported condition comprising arranging a plurality of wet unsupported packages of artificial silk in vertical columns with spacer plates therebetween, with the packages each supporting the column thereabove, passing a drying medium centrally through the columns of packages, continuing the passing of the drying medium through the packages to thereby effect a progressive drying thereof and permit each of the spacer plates and the packages supported thereabove to rest directly upon the packages next below the same and to move downwardly in accordance with the contraction of the respective packages, and gradually relieving each of the contracted packages of the weight of such spacer plates and packages as exist thereabove by otherwise supporting each spacer plate when it is moved into a predetermined spaced relation with respect to the next lower spacer plate, whereby substantially air-tight passages defined by the thread free interiors of the packages are maintained during the drying period with the resultant progressive drying of the packages from the interior to the exterior thereof.
